(57) **CLAIM**

The ornamental design for a vanity as shown and described.

DESCRIPTION

FIG. 1 is a perspective view taken from the front, left, and top of a first embodiment of a vanity of the present application;

FIG. 2 is a perspective view taken from the rear, right, and bottom thereof;

FIG. 3 is a top view thereof;

FIG. 4 is a front view thereof;

FIG. 5 is a right side view thereof;

FIG. 6 is a left side view thereof;

FIG. 7 is a perspective view taken from the front, left, and top of a second embodiment of a vanity of the present application;

FIG. 8 is a perspective view taken from the rear, right, and bottom thereof;

FIG. 9 is a top view thereof;

FIG. 10 is a front view thereof;

FIG. 11 right side view thereof; and,

FIG. 12 is a left side view thereof.

The bottom surface shown in FIGS. 2 and 8 between all broken lines is hidden in use and forms no part of the claimed design. The rear surface shown in FIGS. 2 and 8 that is bounded at its lower edge by a broken line is hidden in use and forms no part of the claimed design. The broken lines in the figures depict portions of the vanity that form no part of the claimed design.

1 Claim, 12 Drawing Sheets
